GAS RANGE BURNER CAP

Frank J. Kindl, Independence, and Birchard L. Matthews,
Cleveland, Ohio, assignors, by mesne assignments, to
Aurora Corporation of Illinois, a corporation of Illinois

Filed June 8, 1960, Ser. No. 60,873

Term of patent 14 years

(Cl. D81—10)

FIG. 1

FIG. 2

FIG. 3

FIG. 1 is a top perspective view of a burner cap showing our new design;

FIG. 2 is a side elevational view thereof, the broken line showing of a gas burner being included for illustrative purposes only; and

FIG. 3 is a top plan view thereof.

All sides of the gas range burner cap are like the side shown in FIG. 2.

We claim:

The ornamental design for a gas range burner cap, as shown and described.
